CLAIM

(56) **References Cited**

The ornamental design for an electronic still camera with a monitor, as shown and described.

U.S. PATENT DOCUMENTS

DESCRIPTION

D. 330,562 * 10/1992 Takada et al. D16/202
D. 402,301 * 12/1998 Sekine D16/202
D. 417,271 * 11/1999 Ikenaga D16/202
D. 425,095 * 5/2000 Watarai et al. D16/217
D. 426,248 * 6/2000 Sumita D16/202

FIG. 1 is a perspective view of an electronic still camera with a monitor showing our design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof; and,

FIG. 7 is a rear elevational view thereof.
